CLAIM

The ornamental design for a ceiling fanlight, as shown and described.

DESCRIPTION

FIG. 1 is a bottom perspective view of a ceiling fan light showing my new design, in a ceiling fan environment;

FIG. 2 is a top perspective view thereof;

FIG. 3 is a bottom plan view thereof; and,

FIG. 4 is a side elevation view thereof.

Broken lines illustrate environmental subject matter and form no part of the claimed design.

1 Claim, 4 Drawing Sheets(56)
